CLAIM

The ornamental design for bottle and cap, as shown and described.

DESCRIPTION

FIG. 1 is a front perspective view of my bottle and cap in accordance with my new design;

FIG. 2 is a top plan view thereof; and,

FIG. 3 is a front view thereof, with rear, left-side elevational and right side elevational views being identical.

The bottom plan view of the bottle and cap is not shown in the drawings or described in the specification and, therefore, forms no part of the claimed design.
